ELECTRIC HEATER MEMBER FOR APPARATUS FOR PERMANENTLY WAVING THE HAIR

Walter Lewis Fry, South Merstham,
Redhill, EnglandApplication January 29, 1946, Serial No. 644,145
In Great Britain February 12, 1945

1 Claim. (Cl. 219—24)

1

This invention relates to electrical apparatus for permanently waving the hair and is concerned more particularly with the heater members adapted to be clipped over the "curls" after these have been formed by winding the hair on suitable curlers.

It is the main object of the invention to provide improved electric heater members which shall be such that they will apply heat substantially uniformly to all points of the curls. Further objects are to construct such heater members so that they will be unaffected by the moisture usually present during the curling operation and be simple to produce and assemble.

According to the invention an electric heater member for the purpose set forth comprises a clip composed of two co-operating spring-closed clamping jaws of heat-conducting material each containing within itself an electric heating element.

The heating elements are preferably wound on a rod, tube or strip of an insulating material, such as porcelain or mica, and, with advantage, are coated or impregnated with an insulating varnish or cement capable of withstanding the normal working temperature of the heating elements, usually about 200° C. The elements may be designed to operate on any normal mains supply of electricity or may be arranged to operate on a relatively low voltage supply delivered, for example, by a step-down transformer connected to a mains supply of alternating current.

As will be understood, the jaws of the heater member are so shaped, e. g. formed of semi-annular cross-section, that, when closed, they will encircle a curler having the hair wound thereon. The heating elements are preferably accommodated in longitudinally extending bores or recesses formed in the respective jaws and may be retained therein by means of end plates. Most suitably they are arranged for electrical connection in series.

In order that the nature of the invention may be clearly understood, an example of a heater member in accordance therewith will now be described with reference to the accompanying drawings, wherein:

Fig. 1 is a sectional elevation, taken on the line I—I of Fig. 4, showing the heater member with electrical connections omitted,

Fig. 2 is a front elevation thereof,

Fig. 3 is a side elevation, and

Fig. 4 is a plan view.

As shown, the heater member comprises two aluminum jaws 1 and 2 of substantially semi-

annular cross-section pivoted together adjacent one longitudinal edge by the aid of a pin 3 engaging aligned apertures in outwardly extending lugs 1a and 2a on the respective jaws 1 and 2.

5 These jaws are normally urged to a closed position (that illustrated) by a rat-trap spring 4 encircling the pin 3 and having its projecting ends engaged with the jaws as shown in Fig. 1. In this setting the jaws enclose a cylindrical 10 space of a size to receive as a close fit the prepared "curl" of hair to be waved, each "curl" being wound on a curler and a protector being disposed between the "curl" and the scalp of the customer to shield the latter from the heated 15 jaws, in the well-known manner.

Insulating handles or finger-grips 5 of similar shape are secured one to each jaw 1 or 2, by means of screws 6 engaging apertures in the lugs 1a or 2a, respectively, in order to facilitate the 20 opening or handling of the jaws and these handles carry terminal elements 7 to each of which electrical connections are adapted to be made at binding screws 7a and 7b.

Each jaw 1 or 2 is thickened adjacent to the 25 pivot 3 and bored longitudinally at 8, through the thickened portion to accommodate an electric heating element 9 composed of resistance wire wound on a rod of porcelain or the like and impregnated with an insulating varnish or cement capable of withstanding the operating 30 temperature of the element. These elements 9 are retained in the bores 8 by end plates 10 secured on the end faces of the jaws by means of screws 11 (see Fig. 3) and are electrically connected in 35 series between the terminal elements 7. The ends of the wire on each element are threaded through passages 12 (shown in Fig. 4) formed in the lugs 1a or 2a, respectively, to be attached to the appropriate binding screws 7a and each conductor 40 of a twin flexible lead (not shown) is connected to one of the binding screws 7b of each jaw, a separate short conducting lead (not shown) being arranged to connect the remaining binding screws 7b of the two jaws together. The twin 45 lead may be replaced by a triple lead having two current-supply conductors connected as just described and a third earthing conductor connected electrically to one of the screws 6, as will be understood.

50 The terminal elements 7 are covered by insulating members 13 secured on the inner surfaces of the handles 5 by screws 14, these members serving also as cord grips to engage the electric leads. The latter may be associated in groups of, say, 55 three and connected as a group to the contacts

of a single connector or adapter which is adapted to be engaged in a socket or the like supplied with electric current and supported in the usual way on the head of a pedestal or standard.

Owing to the location of the heating elements 9 within and, in close, heat-conducting relation to the jaws 1 and 2 which have themselves good heat-conducting properties, the heat generated is effectively utilised in raising the temperature of the jaws uniformly throughout their mass. Furthermore, the heating elements are fully protected against the moisture present in the agents used on the hair and yet the whole heater member is simple to produce and assemble.

What I claim is:

An electric heater member for permanent hair waving comprising a pair of solid semi-annular clamping jaws of heat conducting material pivoted together adjacent one longitudinal edge and thickened towards said longitudinal edge, a

spring urging said jaws to a closed position, a pair of handles of insulating material to open the jaws against the spring, a longitudinally extending bore in the thickened portion of each jaw, an electric heating element in each said bore, connections from the heating elements to a source of supply and plates secured on end faces of the jaws to close the bores and retain the heating elements within the bores.
